Attorney

UNITED STATES PATENT OFFICE.

WILLIAM S. DAVIS, OF SACRAMENTO, CALIFORNIA, ASSIGNOR OF ONE-HALF TO
CHARLES E. EMERSON, OF SUSANVILLE, CALIFORNIA.

BURNER.

1,260,758.

Specification of Letters Patent. Patented Mar. 26, 1918.

Application filed June 11, 1917. Serial No. 174,158.

To all whom it may concern:

Be it known that I, WILLIAM S. DAVIS, a citizen of the United States, residing at Sacramento, in the county of Sacramento and State of California, have invented certain new and useful Improvements in Burners, of which the following is a specification, reference being had to the accompanying drawings.

10 This invention relates to certain improvements in liquid fuel burners and it is an object of the invention to provide a device of this general character having novel and improved means whereby an intense heat may 15 be generated and wherein the creation of odor is substantially entirely eliminated.

It is also an object of the invention to provide a burner of this general character having novel and improved means whereby the 20 requisite mixture of air is assured for supporting combustion and creating sufficient draft to form a flame of material length.

The invention consists in the details of construction and in the combination and arrangement of the several parts of my improved burner whereby certain important advantages are attained and the device is rendered simpler, less expensive and otherwise more convenient and advantageous for 30 use, all as will be hereinafter more fully set forth.

The novel features of the invention will hereinafter be definitely claimed.

In order that my invention may be the 35 better understood, I will now proceed to describe the same with reference to the accompanying drawings, wherein—

Figure 1 is a diagrammatic view partly in elevation and partly in section illustrating a 40 burner constructed in accordance with an embodiment of my invention;

Fig. 2 is a sectional view taken substantially on the line 2—2 of Fig. 1; and

Fig. 3 is a fragmentary elevational view 45 with parts omitted illustrating a slightly modified form of my improved burner.

As disclosed in the accompanying drawings, 1 denotes a supporting basket having its upper end opened and provided adjacent 50 its upper end with an annular series of materially large openings 2. As disclosed in Fig. 1, the basket 1 is tapered toward the bottom and is seated within a suitable opening in a support S, said support being preferably the lower end of a heating device as

particularly disclosed in my accompanying application filed June 11, 1917, Serial No. 174,157. 3 denotes a cup-like member formed of metal and seated within the bottom portion of the basket 1 and which serves as a heat retaining member. Resting upon the bottom of the cup 3 is the main burner M which comprises a hollow body provided at its margin with an annular series of restricted openings 4. The center of the burner M is provided therethrough with a threaded opening 5 and in which is engaged the depending boss 6 arranged at the axial center of the supplemental burner B positioned above the main burner M and in predetermined spaced relation thereto. The supplemental burner B is also of a predetermined diameter less than the diameter of the main burner M. The supplemental burner B is also hollow and provided at its marginal portion with an annular series of restricted openings 7. In communication with the chamber of each of the burners M and B is a supply pipe 8 and 8', respectively, leading from a common source of fuel supply as indicated by the pipe 9. Interposed in the pipe 8 coating with the supplemental burner B is a needle valve 10 adapted to be automatically operated through the medium of a thermostat T whereby the operation of the burner B may be regulated in accordance with the requirements of practice. The second pipe 8 has interposed therein the manually operated needle valve 11 for controlling the flow of fuel through said second pipe 8. Each of the pipes 8 has also interposed therein the glass 12 to afford visual access within the pipe 8 in order to observe the flow of the fuel therethrough.

Surrounding the burner M is a sleeve 14 of a length to terminate above the openings 2 hereinbefore referred to but below the top or open end of the basket 1. Positioned within the sleeve 14 and concentric thereto is a second sleeve 15 which surrounds the supplemental burner B and arranged within the sleeve 15 and concentric thereto is the third sleeve 16. The sleeve 16 rests upon the supplemental burner B at a point inwardly of the restricted openings 7 thereof. The upper ends of the sleeves 15 and 16 are substantially flush with the upper end of the sleeve 14 and the sleeves 14, 15 and 16 are provided with the vertically spaced annular series of restricted openings 17 which serve

to permit the air entering through the openings 2 in the basket 1 to properly support combustion while the sleeves 14, 15 and 16 coact to afford flues to result in sufficient draft being created as to cause the flames of the burners M and B to be of material length. It has been fully demonstrated in practice that the openings 2, which are materially in excess of the areas of the restricted openings 17 coact with the restricted openings 17 in creating a flame free from smoke and which can be maintained at a comparatively small cost. In practice it has been found that the flames of the burners M and B can be maintained on a pint of fuel per hour.

The upper face of the burner B at its axial center is provided with the upstanding lug 18 to afford means whereby a wrench or other implement may be engaged with said burner B when it is desired to apply or remove the same.

The form of my invention as illustrated in Figs. 1 and 2 is particularly adapted for use in connection with a water heater as embodied in my copending application executed on even date herewith. I have found, however, in practice that my improved burner may be employed with convenience and facility in connection with the creation of dry heat. In this latter use the burner is adapted to be connected directly with the lower end portion of a flue F as particularly illustrated in Fig. 3. In so using the upper portion of the basket 1^a at each side thereof is provided with an outstanding pin 19 with which is adapted to coact a substantially L shaped lug 20 depending from the flue F.

From the foregoing description, it is thought to be obvious that a burner constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice, except as hereinafter claimed.

I claim:

1. A device of the character described comprising a basket having its upper end portion provided with openings adjacent its open end, a cup like member resting upon the closed end of the basket, a hollow burner positioned within the cup like member and resting upon the bottom thereof, a second hollow burner arranged within the cup like member and operatively engaged with the

first named burner, each of said burners being provided with restricted openings in their marginal portions, and means for delivering fuel in each of said burners.

2. A device of the character described comprising a basket having its upper end portion provided with openings adjacent its open end, a cup like member resting upon the closed end of the basket, a hollow burner positioned within the cup like member and resting upon the bottom thereof, a second hollow burner arranged within the cup like member and operatively engaged with the first named burner, each of said burners being provided with restricted openings in their marginal portions, means for delivering fuel in each of said burners, and means for controlling the delivery of fuel to each of the burners independently of the other.

3. A device of the character described comprising a basket having its upper end portion provided with openings adjacent its open end, a cup like member resting upon the closed end of the basket, a hollow burner positioned within the cup like member and resting upon the bottom thereof, a second hollow burner arranged within the cup like member and operatively engaged with the first named burner, each of said burners being provided with restricted openings in their marginal portions, means for delivering fuel in each of said burners, a sleeve surrounding the lower burner and extending above the openings in the basket, a second sleeve surrounding the upper burner and extending above the openings in the basket, said second sleeve being positioned inwardly of the restricted openings in the lower burner, and a third sleeve supported by the upper burner inwardly of the restricted openings therein, the third sleeve also extending above the openings in the basket, each of said sleeves being provided with restricted openings.

4. A device of the character described comprising a basket having its upper end portion provided with openings adjacent its open end, a cup like member resting upon the closed end of the basket, a hollow burner positioned within the cup like member and resting upon the bottom thereof, a second hollow burner arranged within the cup like member and operatively engaged with the first named burner, each of said burners being provided with restricted openings in their marginal portions, means for delivering fuel in each of said burners, a sleeve surrounding the lower burner and extending above the openings in the basket, a second sleeve surrounding the upper burner and extending above the openings in the basket, said second sleeve being positioned inwardly of the restricted openings in the lower burner, and a third sleeve supported by the upper burner inwardly of the restrict-

ed openings therein, the third sleeve also extending above the openings in the basket, each of said sleeves being provided with restricted openings, the openings in the basket 5 being in excess of the areas of the openings in the sleeves.

5. A device of the character described comprising a basket having its upper end portion provided with openings adjacent its 10 open end, a cup like member resting upon the closed end of the basket, a hollow burner positioned within the cup like member and resting upon the bottom thereof, a second hollow burner arranged within the

cup like member and operatively engaged 15 with the first named burner, each of said burners being provided with restricted openings in their marginal portions, means for delivering fuel in each of said burners, said cup like member being positioned in the 20 basket below the openings in the basket.

In testimony whereof I hereunto affix my signature in the presence of two witnesses.

WILLIAM S. DAVIS.
